UNITED STATES PATENT OFFICE

156,419

BUTTER DISPENSING MACHINE

Frederick Orlo Johnson, Detroit, Mich.

Application August 8, 1946, Serial No. 132,360

Term of patent 14 years

(Cl. D52—2)

To all whom it may concern:

Be it known that I, Frederick Orlo Johnson, a citizen of the Dominion of Canada and subject of the King of Great Britain, residing at Detroit, Wayne County, Michigan, have invented a new, original, and ornamental Design for a Butter Dispensing Machine, of which the following is a specification, reference being had to the accompanying drawing, forming a part thereof, in which:

Fig. 1 is a front perspective,

Fig. 2 is a rear perspective,

Fig. 3 is a top plan view,

Fig. 5 is a fragmentary side elevation of a butter dispensing machine embodying my new design.

I claim:

The ornamental design for a butter dispensing machine, as shown.

FREDERICK ORLO JOHNSON.
